rage of the
s in a store
of humidifi-
the ageing
s the "wet

twister" method consists in drawing the
yarn through water prior to winding same
on the cones 9. These methods are objec-
tionable, however, due to the expense of
handling and storage of the yarn in the 60
one case and the absorption of too much
moisture by the yarn in the other.

According to my invention a trough 10
is supported from a beam 11 by means of
brackets 12 which project outwardly and 65
upwardly between the aprons 6, the trough
being suitably secured to the ends of these
brackets in position to overlie the aprons.
Mounted to rotate in this trough is a shaft
13 provided with spaced enlargements or 70
sleeves 14 fixed thereto throughout its
length, there being an enlargement for each
spindle 8 and in the path of travel of the
thread 7 from the spindles to the cones 9.
These enlargements are half submerged in 75
the water 15 in trough 6. The shaft 13 is
constantly rotated at a very slow prede-
termined rate of speed by any suitable
means (not shown). The yarn 7 travels at
a very high rate of speed as it is unwound 80
from the spindles 8 and consequently very
little moisture is taken up by the yarn as
it contacts with the enlargements. By regu-
lating the speed of rotation of the shaft 13
to the proper ratio of speed of travel be- 85
tween said shaft and the yarn the amount
of moisture which the yarn will take up can
be regulated to a nicety. In practice it has
been found that cotton yarn gives best re-
sults when containing about 7% moisture. 90

By providing the shaft 13 with the en-
largements 14 a substantial surface is at
all times out of contact with the water in
the trough 6 and consequently comparatively
little moisture is carried by the exposed half 95
of these enlargements. It thus follows that
the yarn cannot become saturated with water
as in the so called "wet twister" method.

In Figure 4 I have illustrated a modifi-
cation of my invention wherein I substitute 100
for the rotary shaft 13 a stationary pipe 16
containing water 17. This pipe is formed
with a number of branch pipes 18 contain-
ing wicks 19. These wicks are adapted to
be positioned in the path of and be engaged 105
by the yarn 7 in its passage between the
spindles 8 and the cones 9.

In Figure 5 a still further modification of
my invention is illustrated wherein a sta-
tionary shaft 19 is substituted for the rotary 110

shaft 13. Loosely mounted for rotation on the shaft 29 are a plurality of rollers 20 which take the place of and function in like manner to the sleeves or enlargements 5 14. The frictional engagement of the yarn with the rollers causes the latter to slowly rotate in the water, it being understood that a trough 6 is employed and also that the rollers 20 are half submerged in the water 10 15 in the trough.

Having thus described my invention what I claim is:

A cone winding machine for winding a plurality of cones, means for winding yarn

upon said cones, means for moistening the 15 yarn, said last mentioned means comprising a water containing trough mounted adjacent the cones, a fixed shaft extending longitudinally of the trough, said shaft being partially submerged in the water, enlargements 20 rotatably mounted on said shaft, there being an enlargement for each cone, said enlargements arranged in the path of the yarn and being engaged and rotated by the yarn as the yarn is being wound on the 25 cones.

In testimony whereof I affix my signature.

ADOLPH A. JOHNSON.
